FURNITURE PACKING

Friedrich H. N. Wohlers, Hempstead, N. Y., assignor to The Hinde & Dauch Paper Company, Sandusky, Ohio, a corporation of Ohio

Application June 1, 1940, Serial No. 338,295

4 Claims. (Cl. 206—46)

This invention relates to a packing for furniture, designed to take the weight of the furniture on a base or frame which can be attached to cross pieces of the furniture so that the weight will not rest on the legs and which will give a foundation and rigid support for a corrugated board cover, without such cover having to take any of the weight and without the cover having to be nailed to any part of the furniture or to any piece which is directly attached to the furniture. This is particularly intended for packing such articles as overstuffed chairs, davenport, and the like although it will be apparent that with suitable modifications it is applicable to other articles. It is shown as applied to a large overstuffed chair.

Since the corrugated board panels of the covering are of large size and present certain difficulties for fastening by staples, it is desirable to have the corrugated board portion partly assembled at the factory in such a way that it can be shipped in knocked-down condition, and set up at the plant without any stapling being done there, but simply by fastening certain joints with tape and by nailing other parts of the board cover to the foundation frame.

In the drawings, which are of illustrative character, and not intended to be limitations upon the scope of the invention,

Figure 1 is a perspective showing the base in full lines and a chain thereon in dotted lines;

Figure 2 is a perspective showing the package applied to the base and partly closed, the portions of the chair which might be visible being omitted for simplicity of the drawings;

Figure 3 shows the package closed and ready for shipment or storage;

Figure 4 is a vertical section on plane 4—4 of Figure 3; and

Figure 5 illustrates the blank as it leaves the box factory, partially assembled but knocked down flat.

The base consists of an outside frame 1 consisting preferably of four pieces of lumber of appropriate weight, fastened with edges up into a rectangular frame of greater area than the floor space covered by the furniture. Two boards 2 are nailed across the top of this frame, set inward from the frame edges so that the furniture cross pieces will rest thereon inside the legs of the article, such as the chair 3, to be packed, and high enough to keep the feet off the floor, as shown in Figure 4. The furniture is fastened to these boards by screws, nails, or the like 4, Figure 4, put up from beneath into a concealed

part, or in other suitable manner so as not to impair the appearance of the furniture.

Referring now particularly to Figure 2, it will be seen that the cover, which is preferably made of corrugated or other box board of suitable weight, consists of three pieces in all, namely two rectangular side panels 5, only one of which is visible in Figures 2 and 3, but both of which are seen in Figure 5, and a cover which is divided by a number of folds into several different panels as will be more fully described.

The cover is preferably, although not necessarily, made of a unitary blank, and divided into panels along folding lines as indicated by dotted lines in Figure 5, thus forming a front 11, lower top 12, upper front 13, upper top 14, and back 15, following one another and all of the same width, set off or defined by the successive transverse fold lines 16, 17, 18, and 19. Each of these panels 11 to 15 inclusive has attaching or closing laps on each of its sides. On panel 11, these are the laps 21, on 12 the laps 22, on 13 the laps 23, on 14 the laps 24 and on 15 the laps 25. The laps 22 are narrow and simply large enough for fastening the side panels 5, whereas the laps 23 close the space above the side panels 5 between the upper front 13, the back 15, and the upper top 14, as will be apparent from Figure 2, which shows the construction partly closed. The long laps 25 close over 23 and 24 after the latter have been put in place, give a complete outer vertical closure reaching all the way from top to bottom, nailed at the bottom and taped at top and front edge, thus adding greatly to the strength of the upper portion 13—14.

At the box factory, the side panels 5 are stitched to the laps 22 as shown in Figure 5, by lines of stitching 32, and the structure is then laid flat but can be turned down along the fold lines 32 when the corrugated board structure is applied to the frame 1, as shown in Figure 2.

To apply the cover, after the furniture piece 3 has been placed on the cross bars 2 and secured thereto, the side pieces 5 and their attaching flaps 22 are turned down along the lines 32, and the side pieces 5 nailed as at 37 to the frame 1. Thus the lower top 12 is across the top of the arms of the chair; in order to apply it the panel 13 has been bent up along the line 17, the panel 14 has been folded back along the line 18, and the front and back panels 11 and 15 turned down along the lines 19 and 16 respectively, after which they are nailed as at 38 to the frame 1. The flaps 21 are turned against sides 5 and taped as at 41, while the laps 23 and 24 are successively turned

into the side plane to close the openings between the edges 13, 14 and 15 above the sides 5. The laps 25 are folded forward over 24 and taped as at 42 and 43.

It will be appreciated that the principles of this invention may be applied in modified forms, differences in details and in particulars of shape and of application being made as may be necessary to fit particular items being packed, the scope of the invention being determined by the following claims.

I claim:

1. A furniture package comprising a closed frame having vertically disposed external sides, and adapted to enclose the legs of the furniture cross pieces secured to the upper edge of said frame at a distance above the floor greater than the downward projection of the furniture legs below said cross pieces, and a cover of self-supporting sheet material including upright sides which are secured only at bottom to all external vertical sides of said frame but only to said sides and covering the furniture but out of contact with any portion of the furniture, said cover comprising two vertical side panels, a back panel and top panels hinged one to another and to the back panel and supported at their ends by said side panels.

2. A furniture package comprising a furniture support and a cover, said support comprising a rigid, closed, rectangular frame of lumber or the like adapted to rest on a floor and having an external upright perimeter, said frame enclosing the furniture legs, cross pieces attached to said frame with their upper surfaces higher above the floor than the downward extent of the furniture legs below furniture cross members, said cross pieces being positioned inwardly of the furniture legs and thereby adapted to support furniture by cross members of the furniture resting thereon; and a cover of corrugated board or the like including upstanding panels supported only by being fastened at their bottoms around the external upright perimeter of said frame, with transverse panels of corrugated board or the like supported thereby and forming with said upstanding panels a complete cover for the packed furniture but carried independently of such furniture.

3. A package for a chair, davenport or the like, comprising a four-sided wood frame with sides

placed edge up, bars on said frame and under the lower horizontal elements of the furniture at a height to hold the furniture legs off the floor, and a boxboard cover comprising four vertical panels nailed to the corresponding sides of said frame, said cover also comprising a panel secured at its edges to three of said vertical panels and horizontally disposed over the arms of the furniture, with a panel rising from the rear of said horizontal panel to the height of the furniture back, joined by a horizontal panel disposed over said back, said last-named horizontal panel being also joined to the one of said four first-named vertical panels which does not join the first named horizontal panel, and laps on said panels which cover the furniture back adapted to fold one over another, and the end lap on said last-named vertical panel being of width equal to that of the last-named horizontal panel.

4. A package for furniture of the seat and back type comprising a rigid four-sided frame of a size to enclose the legs of the furniture and having portions engageable with the furniture between the legs thereof to support the same with the legs clear of the floor, in combination with a cover composed entirely of boxboard and comprising two flat side panels attached at their lower edges to opposite sides of said frame and extending the full length of said sides, a back panel attached at its lower edge to the rear side of the frame and extending the full length thereof, said rear panel being higher than the side panels, a top panel extending forwardly from the upper edge of the back panel, an upper front panel extending downwardly from the top panel, a seat covering panel extending forwardly from the upper front panel and resting upon the upper edges of the side panels, and a lower front panel extending down from the forward edge of the seat covering panel and secured at its lower edge to the forward side of said frame, said back panel having end laps extending the full height thereof and secured to the side panels, said top and upper front panels having end laps secured to one another and to the laps of the rear panel, said seat covering panel and said lower front panel having laps overlying the upper and forward edge portions of said side panels.

FRIEDRICH H. N. WOHLERS.
